COMPRESSIBLE PACKING

Filed Aug. 11, 1928

UNITED STATES PATENT OFFICE

STANLEY IMERMAN, OF DETROIT, MICHIGAN

COMPRESSIBLE PACKING

Application filed August 11, 1928. Serial No. 298,895.

The present invention pertains to a novel compressible packing intended particularly for use in connection with the travelling valves for oil well pumps, although the invention contemplates the use of this packing for whatever purposes it may be suitable.

The travelling valve of the character mentioned above operates after the fashion of a piston in a cylinder but has a valve structure permitting the flow of oil therethrough and through a hollow connecting rod to the surface of the ground. Much difficulty has been experienced in the use of these devices due to imperfect packing between the piston member and the cylinder in which it reciprocates, with a resulting leakage of the oil being lifted and a loss in efficiency. The present invention aims to overcome this difficulty by providing a packing device which is automatically compressed longitudinally and spread radially on each impulse of the piston or valve member.

The invention is fully disclosed by way of example in the following description and in the accompanying drawings in which—

Figure 1 is a longitudinal section of the travelling valve or piston member;

Fig. 2 is a longitudinal section of the cylinder, showing the travelling valve therein in elevation;

Fig. 3 is a section on the line 3—3 of Fig. 1;

Fig. 4 is a perspective view of one of the packing sections;

Fig. 5 is a plan view of a modified construction of packing;

Fig. 6 is a side elevation thereof; and

Fig. 7 is a transverse section of a further modified piston.

Reference to these views will now be had by use of like characters which are employed to designate corresponding parts throughout.

The travelling valve or piston with which this invention is concerned is adapted to slide in an elongated cylinder 1 which is dropped into a bore in the ground in the usual manner. The lower end is perforated as at 2 to permit influx of oil without an excessive quantity of solid matter. Above the perforated end is mounted a valve seat 3 on which

rests a downwardly closing ball 4 to prevent the return of oil which has been drawn upwardly by the piston.

The valve seat includes a hollow head 5 at its upper end provided with a stud 6 which threads into a hollow connecting rod 7 as shown in Fig. 2. The head has opposed portions 8 beneath which is supported an internal ring or valve seat 9 on which rests a ball 10. The lower end of the head threads over a tubular body 11 which also serves to hold the seat 9 in place.

The lower end of the tube has an outward shoulder 12 surrounded by a retaining member 13 having an inner shoulder 14. A spring 15 disposed between the shoulders serves to hold the retaining member in an elevated position. Above this ring, the tube 11 is surrounded alternately by lead packing rings 16 and a retaining ring 17, these members depending for their support on the member 13.

Over the top ring 16 a spacer 18 is threaded on the tube and is formed at its upper end with a shoulder 19 to assist in retaining the ring formed by the juxtaposed members. It will be seen however, that these members fail to close a circle and thus leave spaces 23, as shown in Fig. 3, to permit expansion. The upper edge of each thicker portion 21 has a ledge or tongue 24 to assist in supporting a second set of segmental members 25 placed against the thin portions 20 to overlap or cover the joints therebetween. The member 25 has at its lower end a tongue 26 received behind the tongue 24 in order to interlock with the first mentioned segments 20—21. One of the segments 20—21 of the first named series has a lug 27 extending laterally therefrom. This lug is received between two adjacent members 25 and holds them against shifting, so that they permanently overlap the joints between the members 20—21.

Over the angular series thus formed is mounted a spacer 28 having an upper ledge 29 and a lower ledge 30. The latter is received adjacent tongues 31 on the members 25 whereby the latter are held against falling out. The upper ledge 29 is received in the grooves 22 of the superjacent series, and it will be apparent that as many of such series as de-

sired may be provided, with the spacers therebetween. The head 5 has a shoulder 32 at the lower end thereof for retaining the tongues 31 of the upper series of members 25.

5 Each packing thus formed is spaced as at 32 from the outer wall of the tube 11, and in this space is fitted a split cylindrical spring 33 which bears against the packing and holds it distended. The tube is perforated at 34 in
10 communication with the spaces 32 so that the fluid carried by the travelling valve further serves to expand the packings against the inner wall of the cylinder 1. In the event that solid particles carried along with the oil
15 should adhere to the inner wall of the cylinder 1, it will be apparent that the packings will yield rather than become distorted or mutilated by the obstruction.

In the modification shown in Figs. 5 and 6
20 there are two series of similar segmental members inverted with respect to each other. These members are of T-shaped formation comprising a head 35 and a stem 36. Alternate members are positioned upright, and the
25 intermediate members are inverted, with their heads 35' between the stems 36, and the stems 36' between the heads 35.

The modification shown in Fig. 7 is similar
30 to that in Figs. 1 and 4 with the exception of the spring. The spring in this case is a split wire 37 received in grooves 38 formed in the inner walls of the members 21. These grooves are provided although a cylindrical
35 spring 33 is used, so that either mode of assembly is available.

Although specific embodiments of the invention have been illustrated and described, it will be understood that various alterations in the details of construction may be made
40 without departing from the spirit and scope of the invention as indicated by the appended claim.

What I claim is:—

In a travelling valve, a tubular body, a
45 compressible packing thereon consisting of a series of segmental members arranged in a ring, each such member having a thin portion and a thicker portion at opposite sides of an arcuate line thereon, additional segmental members placed adjacent said thin portions and overlapping the joints therebetween, a spring disposed within the series of
50 first named segmental members and bearing outwardly thereon, and locking means between said thicker portions and the last named segmental members.

In testimony whereof I affix my signature.
STANLEY IMERMAN.
